O. J. KUHLKE

TUBE VULCANIZER

Filed Jan. 18, 1927

UNITED STATES PATENT OFFICE.

OTTO J. KUHLKE, OF AKRON, OHIO, ASSIGNOR TO THE KUHLKE MACHINE COMPANY,
OF AKRON, OHIO, A CORPORATION OF OHIO.

TUBE VULCANIZER.

Application filed January 18, 1927. Serial No. 161,786.

This invention relates to apparatus for the vulcanization of inner tubes and particularly to improvements in that type of vulcanizer in which the tube is cured while 5 in circular condition and while the interior of the tube is expanded by internal fluid pressure.

The invention does not relate to the general structure of vulcanizers of this type, but 10 to the means for receiving or housing the valve stem of the tube, so that the application does not include details of the vulcanizer mechanism as they form no part of the present invention. In fact, the features of the 15 present invention are adaptable for use with many different types of vulcanizers.

In the manufacture of inner tubes, the operator is called upon frequently to cure tubes having straight valve stems and then tubes 20 having bent valve stems, both types of valve stems being used with inner tubes. Heretofore, tube vulcanizing apparatus suitable for curing tubes with one type of valve stem has not been suitable for curing tubes with other 25 types of valve stems without making considerable changes in the apparatus, and changes from one to the other have not been readily made. The present apparatus is designed to receive and accommodate either type of 30 valve stem, the change being made easily and quickly, and to this object the invention is directed.

A further object of the invention is to 35 provide means for clamping the valve stem so that it may be retained during the vulcanizing operation with the base of the valve stem out of contact with the inner tube wall; but should leakage occur about the valve stem, it may be released whereupon pressure 40 within the tube will force the base of the stem in contact with the tube wall, sealing the space about the valve. This aspect of the invention is the same as that covered in my prior application, Serial No. 146,913, 45 filed November 8, 1926, of which this application is a continuation in part.

In the drawings which form a part of this 50 application, the preferred form of the apparatus is shown and the description thereof in the specification is directed particularly to that form, but it will be appreciated that the invention is not limited in its scope or operation to exact conformity therewith and changes and modifications may be made

within the statement of the invention and as 55 set forth in the claims.

In the drawings:

Figure 1 is a cross-section through a tube vulcanizer taken at the valve stem and showing the invention in place therein and with 60 straight and bent valve stems in position;

Figure 2 is a side view thereof;

Figure 3 is a sectional view showing the means of operating the device for a bent valve stem; and 65

Figure 4 is a detail section on the line 4—4 of Figure 1.

The vulcanizer which has been illustrated as a form or type of vulcanizer to which my 70 invention may be applied, comprises a central ring-shaped and steam chambered vulcanizer section 1 which is supported by a bracket 2 from a frame or support 3.

The outer surface of the member 1 is 75 formed with a curved trough or cavity 4 which constitutes the inner cavity of the tube mold, the molding cavity being completed by an outer expandable jacket consisting of two steam chambered halves 5 and 6, the inner surfaces of which are formed with trough-like cavities 7 which, with the recess 4, completes the cavity for the tube 10. The valve stem for the tube, which may be either straight or bent, is indicated at 11 and 12, the former being a straight valve and the 80 latter a bent valve. During the process of vulcanization the interior of the tube is connected through piping 15 with a source of fluid under pressure.

The mold 1 at the valve stem is cut away 90 to form a lateral guideway 20 in which is slidably mounted a block 21 having flanges 22 thereon which are held in place by plates or rails 23. The mold is provided with an approximately semi-circular recess 24 for the 95 reception of one side of the valve stem and the inner end of the slide block is formed with a similar recess 25, the two recesses closely encircling the valve stem at the base where either type is radial to the tube. 100 These recesses may be flattened slightly to accommodate the flattened sides of the valve stems. The upper inner surface of the slide block is cut away at 27 to conform to and form a smooth continuation of the inner surface of the molding cavity. The inner or under side of the slide block is formed with a groove 28 in which is received the hori-

zontal portion of the bent valve stem as shown in Figure 1.

The straight valve stem may be inserted and removed without operating the slide block, but when the bent valve stem is inserted it is necessary to move the slide block outwardly to the position shown in Figure 3. In order to provide a stop for the outward movement of the slide block, a shallow 10 groove 30 is formed for a short distance inwardly on the block and on the mold section 1 is pivoted on bolt 31 a weighted handle 32 having an ear 34 which rides in the groove and abuts against the end thereof to 15 arrest outward movement of the block. The handle or lever 32 also affords a lock for the slide at its inner position, being designed to pass over the end of the block and clamp it in position. To obtain a firm locking of 20 the slide block in its innermost position the outer surface of the block is downwardly and outwardly inclined, as indicated at 35 in Figure 1, and the lever is confined by a bridge piece 36 so that as the lever is 25 brought down the block 21 is securely clamped in position.

Located within the block is a longitudinal pin 40, a portion of which is in screw-threaded engagement with the block and the 30 inner end of which is arranged to bear against and clamp the valve stem in position. The outer end of the pin is provided with a handle 42 by which it may be turned and which also affords an easy hold for operation of the slide block. In the process 35 of vulcanizing, it is desirable that the valve stem be clamped in position so as to assist in connecting the pressure line 15. If desired the valve stem may then be released to 40 move while the pressure is being applied so that the tube may seat properly in the cavity, and after the tube has been seated and when vulcanization has commenced and the rubber of the tube is softened, it may be 45 desirable to permit the valve stem to embed in the rubber and then to clamp the valve stem to prevent it being forced through the wall of the tube. To accomplish this the pin 40 may be tightened and loosened to 50 release or clamp the valve stem in accordance with the particular stage of the process. The clamp may also be used to hold the base of the valve stem out of contact with the inner wall of the tube, unless leakage 55 occurs about the stem, whereupon the stem may be released momentarily so that the pressure within the tube will force the base of the stem against the tube wall closing the leak.

60 It is thought that the operation of the apparatus will be clear from the description which has been given and further details are unnecessary. In so far as known to me, the described construction is the most practical 65 and easily operated device of its kind for

vulcanizing tubes with either type of valve stem. No changing of the apparatus is required and the tubes may come to the operator indiscriminately as to the type and character of valve stem employed, as both 70 types can be readily handled and placed in position without changes in the equipment. Other objects and advantages will be apparent from the description and such features as are broadly new are intended to be covered in the claims appended hereto. 75

The curved upper surface of the slide block is a valuable feature of the invention, it being noted that as this surface intersects the toric surface on the interior of the mold 80 cavity, the angle at which the surfaces meet is blunt and substantially a right angle entirely about the opening when the section represented by the end of the block is removed. As a result, no sharp or feathered 85 edge or surface is generated, which, if present, would chip or break.

What is claimed is:

1. A tube vulcanizer comprising a sectional mold, one of said sections having a 90 trough-shaped cavity for the inner surface of the tube, the lower portion of the cavity having an opening therein sufficient to permit the passage of a bent valve stem, and a movable block received in the opening and 95 completing the molding cavity, an aperture for the base of the valve stem being formed partially in the block and partially in the mold section.

2. A tube vulcanizer comprising a sectional mold, one of said sections having a 100 trough-shaped cavity for the inner surface of the tube, the lower portion of the cavity having an opening therein sufficient to permit the passage of a bent valve stem, a lateral 105 slideway formed in the mold section leading from the opening, and a block movable in the slideway, an aperture for the base of the valve stem being formed partially in the block and partially in the mold section. 110

3. A tube vulcanizer comprising a sectional mold, one of said sections having a 115 trough-shaped cavity for the inner surface of the tube, the lower portion of the cavity having an opening therein sufficient to permit the passage of a bent valve stem, a lateral slideway formed in the mold section leading from the opening, a block movable in the slideway, an aperture for the base of the valve stem being formed partially in the 120 block and partially in the mold section, and means to lock the block in its innermost position.

4. A tube vulcanizer comprising a sectional mold, one of said sections having a 125 trough-shaped cavity for the inner surface of the tube, the lower portion of the cavity having an opening therein sufficient to permit the passage of a bent valve stem, a movable block received in the opening and com- 130

pling the molding cavity, an aperture for the base of the valve stem being formed partially in the block and partially in the mold section, and means to secure the block 5 in position within the mold.

5. A tube vulcanizer comprising a sectional mold, one of said sections having a trough-shaped cavity for the inner surface of the tube, the lower portion of the cavity 10 having an opening therein sufficient to permit the passage of a bent valve stem, a lateral slideway formed in the mold section leading from the opening, a block movable in the slideway, an aperture for the base of the 15 valve stem being formed partially in the block and partially in the mold section, and a valve securing pin mounted in the block.
6. A tube vulcanizer comprising a sectional mold, one of said sections having a 20 trough-shaped cavity for the inner surface of the tube, the lower portion of the cavity having an opening therein sufficient to permit the passage of a bent valve stem, a lateral slideway formed in the mold section 25 leading from the opening, a block movable in the slideway, an aperture for the base of the valve stem being formed partially in the block and partially in the mold section,

means to lock the block in its innermost position, and a pin screwed in said block and 30 having an inner end to bear against and clamp the valve stem within the aperture.

7. An apparatus for the vulcanization of inner tubes comprising separable mold sections adapted to provide a chamber for the 35 tube, a passageway being formed in the mold for the valve stem, and a device operable, while the mold is closed, in one direction to grip the valve stem and hold it from longitudinal movement and in the opposite direction 40 to release the valve stem to permit free movement of the stem through the passageway.

8. An apparatus for the vulcanization of inner tubes comprising separable mold sections adapted to provide a chamber for the 45 tube, a passageway being formed in the mold for the valve stem, and a set screw operable, while the mold is closed, in one direction to grip the valve stem and hold it from longitudinal movement and in the opposite direction 50 to release the valve stem to permit free movement of the stem through the passageway.

OTTO J. KUHLKE.
